Attorney.*

UNITED STATES PATENT OFFICE

GEORGE GARWOOD NEIDICH, OF NUTLEY, NEW JERSEY, ASSIGNOR TO NEIDICH PROCESS COMPANY, OF BURLINGTON, NEW JERSEY, A CORPORATION OF DELAWARE

CARBON-SHEET CARTON

Application filed January 19, 1928. Serial No. 247,779.

Ordinarily, carbon paper is packed in cartons containing only one color, kind, and grade. However, it is most economical to employ carbon paper of four different grades for making record copies of ordinary commercial typewritten matter, including correspondence, bills, order forms, etc.; such transfer sheets ranging from seven pound tissue paper stock for single copies to four pound stock for six or more copies.

It is not only costly, but difficult, and consequently wasteful of time of the typist, to maintain and use a stock of the four different grades, because in accordance with the usual practice, it would necessitate the maintenance of four different bulky cartons in a position accessible to the typist.

Therefore, it is the object and effect of my invention to provide means for packing, and rendering accessible to a typist in a single carton, the several grades of carbon paper sheets aforesaid and in such position and relation that the different grades are distinctively and accessibly presented for withdrawal by the operator; the paper of the several grades being held in respectively different folders which are primarily packed in said carton but which may be readily independently removed and replaced. Moreover, an adjunctive feature of my invention is the distinguishment of each of said folders by color, coordinating them and their contents with the colors of paper ordinarily used in the several items of commercial stationery contemplated upon which the original typewritten matter is imprinted. It is the ordinary practice to employ four different kinds of commercial papers, respectively white, blue, pink and yellow; the white being the thickest and the yellow the thinnest. Therefore, in the form of my invention hereinafter described, I have included in a single carton, respective folders which are white, blue, pink and yellow and which hold carbon paper of the proper grade for making copies from the original typewriting upon paper which is white, blue, pink and yellow and differing in thickness as aforesaid. The advantage of such arrangement is that an unskilled or careless typist may be sure to use the proper grade of

carbon paper by taking it from the folder which is identified with the same color as the paper upon which the original ribbon copy of the matter to be typed is to be written.

My invention includes the various novel features of construction and arrangement hereinafter more definitely specified. 55

In said drawings; Fig. I is a plan view of a carton conveniently embodying my invention. 60

Fig. II is a sectional view of said carton, taken on the line II, II in Fig. I; merely one long side of the carton being removed.

Fig. III is a sectional view, similar to Fig. II, but showing a modified form of abutment fixed in the carton. 65

Fig. IV is a perspective view of the abutment block which is fixed in the carton in Fig. II.

Fig. V is a fragmentary perspective view 70 of the abutment panel which is fixed in the carton in Fig. III.

Fig. VI is a perspective view showing the carton in opened position with each of the four grades of carbon paper immediately accessible to the operator. 75

Fig. VII is a fragmentary side elevation of one of the folders in opened position.

In said figures; the carton 1 is of rectangular configuration and has the flap closure 2 at one end which is hinged to the bottom panel 3 at their junction 4. Said flap 2 is normally upturned in the position shown in Fig. II and covered by the closure 6 which is hinged to the carton 1 at their junction 7 so 80 that the side walls 8 of said carton are then inclosed by the side walls 10 of said closure 6 and the end closure 2 secured by the overlapping end wall 11 of said closure 6. 85

However, as shown in Fig. VI; the closure 6 may be turned back upon the top of the carton casing 1 so as to release the end flap 2 and permit it to fall flat upon the surface supporting said carton, thus exposing in readily accessible position, the four folders 13, 14, 15, and 16 which are preferably respectively colored white, blue, pink and yellow and which respectively hold supplies of carbon paper 18, 19, 20 and 21 ranging from seven 90 pound to four pound stock. 95

Each of said folders 13, 14, 15 and 16 has a bottom panel 23 in rigid relation with a solid hinge abutment 24, and a top flap panel 25 which is hingedly connected, at 26, to the abutment 24 of its bottom panel 23. Said abutments should be of such extent as to overlap, as shown in Figs. II and III, to solidly fill the rear end of the carton, and thus frictionally engage said folders with the carton and each other, and thus normally detain said folders in the desired stepped relation shown, regardless of whether they are partly filled or empty. Said holders are respectively of substantially the same length and other dimensions; so as to minimize the cost of production thereof.

The construction and arrangement of the carton casing 1 is such that although the walls thereof are in permanent substantially rigid relation; they are formed of pliable sheet material, such as pasteboard, having sufficient elasticity to afford a clamping action upon such solid abutments 24 of a group of folders, to normally retain the latter in the position shown in Figs. II and III. However, the construction and arrangement of said folders is such that each of them may be readily removed and replaced with respect to the carton casing 1, and each may be freely opened, as indicated in Fig. VII, to afford convenient access to the carbon paper therein which may be thus readily removed and replaced.

In order to present the folders in the cartons with their front ends in stepped relation so that they are readily separately accessible, as shown in Fig. VI; I provide the carton 1 with an abutment fixed in the rear end thereof and having its front end extending in a plane oblique to the plane of the carton. In the form shown in Figs. II and IV; the abutment fixed in the carton 1 is a solid block 28, preferably of wood, which is permanently cemented to the walls of the carton and has steps 29 at its front end adapted to receive and fit the respective folders, in the position shown in Fig. II.

However, in the form of my invention shown in Figs. III and V, the abutment which is fixed in the carton 1 is a panel of sheet material 31, which is primarily plane but provided with flanges 32 at its opposite ends extending rearwardly in the carton and cemented to the opposite side walls of the latter.

Although I prefer to embody my invention in a carton including a congeries of four folders for respectively different grades of carbon paper, any plural number may be employed.

The unstepped form of the carton abutment disclosed herein is the subject matter of my divisional application Serial No. 333,447 filed January 18, 1929.

Therefore, I do not desire to limit myself to the precise details of construction and arrangement herein set forth, as it is obvious

that various modifications may be made therein without departing from the essential features of my invention, as defined in the appended claims.

I claim:

1. A carbon sheet carton having fixed therein, at the rear end thereof, an abutment having steps at its front end; and including a congeries of distinct and separable folders, each having a bottom panel and a solid abutment in rigid relation therewith, for engagement with the front of said stepped abutment, and a top panel, hinged to said folder abutment and of such extent as to overlap one of said steps and adapted, when closed, to extend parallel to said bottom panel; said folder abutments being adapted to solidly fill the rear end of the carton, in frictional engagement therewith; whereby the free ends of said folders are normally detained in stepped relation in said carton.

2. A structure as in claim 1: wherein the container is hollow and formed of flexible resilient sheet material.

3. A structure as in claim 1: wherein the stepped abutment fixed therein is a solid block of rigid material.

4. A structure as in claim 1: wherein the container is hollow and formed of flexible resilient sheet material, and the abutment fixed therein is a solid block of rigid material.

5. A carbon sheet carton having fixed therein, at the rear end thereof, an abutment having its front end sloped so as to be nearer to the front of the carton at the bottom thereof than at the top; said carton having top and bottom walls connected by side walls holding said top and bottom walls in parallel relation; and a congeries of distinct and separable folders, each having a solid abutment in rigid relation therewith, adapted to bear upon said carton abutment; each of said folder abutments being of such extent as to overlap the adjoining folder abutment and solidly fill the rear end of said carton in frictional engagement therewith; whereby the free ends of said folders are normally detained in stepped relation in said carton, regardless of whether they are partly filled or empty.

In testimony whereof, I have hereunto signed my name at Burlington, New Jersey, this 3rd day of January, 1928.

GEORGE GARWOOD NEIDICH.

CERTIFICATE OF CORRECTION.

Patent No. 1,769,595.

Granted July 1, 1930, to

GEORGE GARWOOD NEIDICH.

It is hereby certified that error appears in the printed specification of the above numbered patent requiring correction as follows: Page 2, lines 79 and 80, claim 1, strike out the words "and of such extent as to overlap one of said steps" and insert the same to follow after the word "abutment" in line 77, claim 1; and that the said Letters Patent should be read with this correction therein that the same may conform to the record of the case in the Patent Office.

Signed and sealed this 5th day of August, A. D. 1930.

(Seal)

Wm. A. Kinnan,
Acting Commissioner of Patents.
